UNITED STATES PATENT OFFICE.

FERDINAND DRUEKE, OF BRIDGEPORT, CONNECTICUT.

WIG-FORM HOLDER.

SPECIFICATION forming part of Letters Patent No. 239,468, dated March 29, 1881.

Application filed June 9, 1880. (No model.)

To all whom it may concern:

Be it known that I, FERDINAND DRUEKE, a citizen of the United States, residing at Bridgeport, Connecticut, have invented new and useful Improvements in Attachments for Wig-Formers, of which the following is a specification.

My invention relates to certain new and useful improvements in holders for wig-forms. 10 It has for its objects to permit of the ready attachment of the ordinary wig form or block and the universal adjustment of the same; and with these objects in view my invention consists of a metallic base provided with a central screw-threaded opening, a vertical stem 15 formed of two or more pieces threaded at the bottom ends and flared at the top to form a socket, and a ball with a radial projecting arm provided with a screw-thread, the ball and 20 socket being secured in place by a surrounding adjusting-ring, as will be hereinafter more fully set forth.

In the manufacture of wigs an ordinary block or skull is employed as a former, and 25 the artisan holds the same upon the lap, turning it as often as may be necessary to properly lay and fasten the hairs. It has been found very tedious and irksome to manipulate such blocks, and from practical experience I have devised and constructed the improved device made the subject of my invention.

In order that those skilled in the art may make and use my invention, I will describe 35 the construction and operation of the same, referring by letter to the accompanying drawings, in which—

Figure 1 is a perspective view of my improved block or form-holder, and Fig. 2 a detail view, showing one-half of the vertical stem with the ball therein.

Similar letters indicate like parts in both figures.

A is a simple metallic base, formed with a 45 central opening threaded, as will be presently more fully explained, and provided with any number of screw-holes, *a*, by means of which said base may be rigidly secured to any kind of a pedestal.

B is a stem, formed preferably of two parts. The lower ends are threaded, as seen at *b*, Fig. 2, thus enabling them to be secured to the threaded central opening of the base A. The upper ends of the stem-pieces are flared 55 outwardly at C to form a ball-socket, within

which is received and held a ball, D, which has projecting radially from it a short screw-threaded arm, E, adapted to screw into the usual wig-manufacturer's form-block or skull F. (Shown in dotted lines.) The top edge of 60 the socket C extends above the center of the ball D, and the latter is clamped firmly at any and varying position by a split ring, G, having projecting ears or lugs H, through which a screw, I, passes, this screw having a square 65 head, adapting it to be readily operated by a key, J. The ring G in cross-section is concentric with the socket C, so that when loosened to permit adjustment of the ball the ring will not become detached or misplaced. 70 The stem is formed of two pieces, adapted to form, when screwed into the base-piece, a vertical stem and socket, and, being formed of two pieces, the socket portion may be made with great facility.

It will be readily seen that, the base A being secured to a suitable pedestal or stand, the ordinary block may, by means of the screw-threaded arm E, be readily secured in position, and that the same may then be adjusted 80 to any desired position almost instantaneously, and the artisan enabled thereby to work in a much less cramped or constrained position than usual.

It will be observed that the top edge of the 85 socket proper throughout its entire extent lies in a horizontal plane at or slightly above the horizontal axis of the ball, so that when the arm E is turned down to its fullest extent the ball and arm may be freely rotated around a 90 vertical axis.

I am aware that ball-and-socket joints are not new, broadly, and do not wish to lay any claim thereto; but

What I claim as new, and desire to secure 95 by Letters Patent, is—

A wig-form holder consisting of a central stem, B, made in two parts, threaded at the bottom, and flared at the top to form a socket, C, a base-piece, A, a ball, D, provided with a projected screw-threaded arm, E, a tightening-ring, G, and hand-screw I, all constructed and arranged in the manner and for the purpose set forth.

In testimony whereof I have hereunto set 105 my hand in the presence of two subscribing witnesses.

Witnesses: FERDINAND DRUEKE.

HERMAN GAUSS,
RUDOLPH KOST.
